(57) CLAIM

The ornamental design for a combination shot glass and golf tee, as shown and described.

DESCRIPTION

FIG. 1 is a perspective view of a combination shot glass and golf tee, showing our new design;

FIG. 2 is a front elevational view of FIG. 1, the rear elevational view being a mirror image thereof;

FIG. 3 is a top plan view of FIG. 1;

FIG. 4 is a bottom plan view of FIG. 1; and,

FIG. 5 is a cross-sectional view thereof, taken along line 5-5 of FIG. 3.

1 Claim, 5 Drawing Sheets
